UNITED STATES PATENT OFFICE.

RALEIGH J. CLANTON, OF DALLAS, TEXAS.

DEVICE FOR THREADING SHIPPING TAGS.

Application filed January 25, 1926. Serial No. 83,510.

This invention is a device for affixing the usual wire fastenings to shipping tags and the like, the primary object being to provide means for eliminating the necessity of attaching these fasteners by hand and to so form the device that it may be employed in conjunction with wire cutting and twisting means to automatically perform the fastener affixing operation.

Another object is to provide in a device of this character, a tag holder rigidly mounting a guiding means to which the fastener forming element is directed from a spool through grommets carried by the carrier, such guiding means forming a loop encircling a portion of the tag body.

Other objects of the invention will be in part obvious and in part pointed out herein-after.

In the accompanying drawings forming a part of this application:—

Figure 1 is a side elevation with parts shown in section, the path of travel of the fastener forming element from the feed rollers being shown.

Figure 2 is a front elevation of the tag receiving pocket and fastener guiding means.

Figure 3 is a fragmentary plan view of the front end portion of the pocket and guiding means.

Figure 4 is a view taken substantially on the line 4—4 of Figure 3,

Figure 5 is a vertical transverse sectional view taken substantially on the line 5—5 of Fig. 4, and

Figure 6 is a plan view of a tag to which a fastener has been applied by my device, the extended portions of the wire being in position to be twisted together.

The herein described device may be employed in conjunction with any preferred standard type of wire cutting and twisting mechanisms, so that its function may be automatically performed. I have for the sake of clarity confined my illustrations to the tag holding and fastener guiding means per se.

Having particular reference to the accompanying drawings in which similar characters of reference designate similar parts, the numeral 8 has reference to the main body which is preferably, although not necessarily, in the form of a relatively long flat member 8 having a horizontal furcation forming upper and lower arms 9 and 10 and

incidentally a tag receiving pocket 11 having flat upper and lower faces so spaced as to readily accommodate any standard sized tag. It will be noted that the tag receiving pocket 11 is open at the outer end and at both side edges, though obviously one of these side edges could readily be closed.

Formed in the outer end portions of these arms 9 and 10 are substantially vertically aligned longitudinal slots 12 and 13, these slots, as is clearly shown in Figure 4, opening through the outer ends of the arms 9 and 10 for reasons hereinafter described.

The device is to be used in the affixing of fasteners to tags such as illustrated in Figure 6, and in which a pair of spaced grommets is carried by the tag, the lengths of the slots 12 and 13 being slightly greater than the distance between the grommet carrying end of the tag and the grommet or eyelet remote from this end. This point is clearly shown in Figure 4. As above stated, the slots 12 and 13 are not truly vertically aligned but diverge toward the free end of the arms 9 and 10 so that the fastener forming element which is drawn from a spool (not shown) may be directed in a spiral course for threading through the grommet or eyelet 14 of the tag 15 in order that the fastener forming element which in this instance is in the form of the usual wire 16, may be passed through the eyelet or grommet 14 to encircle portions of the tag body.

The guiding means for directing the fastening means through the grommets or eyelets 14 consist of the formation of a pair of outwardly directed arcuate bars 17 which are preferably integrally formed with the upper and lower arms 9 and 10 and are spaced inwardly a relatively short distance from the outer ends of the upper and lower slots 12 and 13. The inner face of each of these bars 17 is formed with a channel or way 18, these ways being so related that the wire 16 in passing through them will assume a substantially spiral formation permitting the fastening element to freely pass through the grommet 14 adjacent the edge of the tag, in both directions for obvious reasons. An upwardly outwardly curved deflecting finger 19 is carried by the upper arm 9 at the point of juncture of the arcuate bar 17 and the outer end portion of said arm. This arm or finger 19 is adapted to

engage the extremity of the fastener forming element at a predetermined period of the attaching or affixing operation.

In the operation of this device, wire or the like is fed from a spool or coil (not shown) between feed rollers 20 and through the front end portion of the lower slot 13, at which point it enters the way or channel 18 of the upper arcuate bar 17 and continues its spiral course, entering the way 18 in the lower arcuate bar 17 and passing for a second time through the eyelet 14 adjacent the edge of the tag and into contact with the lower curved face of the deflecting finger 19. At this stage, the wire 16 may be cut at a point between the feed roller 20 and the tag holding or receiving pocket, after which the two extensions 21 may be gripped and pulled longitudinally and outwardly from the ends of the arms with the result that the wire is looped around the portion of the tag body lying between the two grommets or eyelets 14. With completion of this operation the extensions 21 may be twisted at the points adjacent the edge of the tag body after which the tag fastener affixing operation is complete.

Manifestly, the construction shown is capable of considerable modification, and such modification as is within the scope of my claims, I consider within the spirit of my invention.

I claim:

1. In a device for affixing a wire or the like fastener to a tag having an eyelet; the combination of a tag receiving pocket having openings in its walls for alignment with the eyelet, and means associated with the pockets and openings for directing a fastener forming element through the eyelet and to form extensions of the fastener beyond the tag to be twisted together and secured to an extraneous member.
2. In a device for affixing a wire or the like fastener to a tag having an eyelet; the combination of a tag receiving pocket having openings in its walls adjacent the eyelet, and arcuate guides associated with the pocket and openings to loop a fastening element through the eyelet and form extensions of the fastener beyond the tag to be twisted together and secured to an extraneous member.
3. In a device for attaching wire or the

like fasteners to tags having eyelets, a pair of spaced parallel arms forming a tag receiving pocket therebetween, said arms having opposed longitudinal substantially aligned slots opening through one end, and arcuate guides arranged outwardly of the slots and aligned therewith to direct the fastener forming element in a substantially circular path and through the tag eyelets.

4. In a device of the character described, a pair of spaced parallel arms forming a tag receiving pocket therebetween and having a pair of substantially aligned longitudinally extending slots opening through one end, and arcuate bars arranged outwardly of the slots and aligned therewith, said bars having ways in their inner faces to guide a fastener forming element in a substantially spiral path for threading through eyelets in a tag.

5. In a device of the character described, a pair of spaced parallel arms forming a tag receiving pocket and having a pair of substantially aligned longitudinally extending slots opening through one end, and outwardly curved guide ways aligned with the slots to direct a fastener forming element in a substantially spiral path for threading through the eyelet of a tag.

6. A structure as specified in claim 5, said guide ways being spaced inwardly from the outer ends of the slots and fastener deflecting means for directing a free end of the fastener radially from the guide ways.

7. In a device of the character described, a pair of arms spaced apart to form a tag receiving pocket having an open end, and also having a pair of longitudinally extending slots opening through said ends, a pair of arcuate guide ways rigidly carried by the arms and aligned with said slots, one end of each guide way being spaced inwardly from the open end of said pockets, and a curved deflecting finger partially overlying the other end of one slot.

8. In a device of the character described, a horizontally disposed card receiving pocket having an open end, a pair of substantially vertically aligned slots opening to said end and guide means for directing a fastener forming element across said pocket and through the eyelets in a tag.

In testimony whereof I affix my signature.

RALEIGH J. CLANTON.
